US0D1086175S

(12) **United States Design Patent** (10) **Patent No.:** **US D1,086,175 S**
(45) **Date of Patent:** **** Jul. 29, 2025**

(54) **DISPLAY SCREEN WITH A GRAPHICAL
USER INTERFACE**

(71) Applicant: **Loadcomplete Co., Ltd.**, Gyeonggi-do (KR)

(72) Inventors: **Jeong Hyun Bae**, Gyeonggi-do (KR); **Soo Jeong Bae**, Gyeonggi-do (KR)

(73) Assignee: **Loadcomplete Co., Ltd.**, Gyeonggi-Do (KR)

(**) Term: **15 Years**

(21) Appl. No.: **29/917,614**

(22) Filed: **Nov. 21, 2023**

(51) **LOC (15) Cl.** **14-04**

(52) **U.S. Cl.**

USPC **D14/485**

(58) **Field of Classification Search**

USPC **D14/485-495**

(57) **CLAIM**

The ornamental design for a display screen with a graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen with a graphical user interface.

The broken lines illustrate a display screen, which forms no part of the claimed design.
